AERIAL MOUNTING

Douglas W. Mitchell, Ottawa, Ontario, Canada,
assignor to Electronic Laboratories, Inc.

Application October 15, 1942, Serial No. 462,169

3 Claims. (Cl. 250—33)

My invention relates in general to mountings for aerials and more particularly to a tilttable mounting for aerials which allows the aerial to bend over as the vehicle upon which it is mounted passes under trees or other obstructions.

My invention finds particular utility in connection with mounting aerials upon the top of vehicles which may be used to travel through woods and underbrush which may engage the aerial and tilt it back as the vehicle moves forwardly. The invention may be used upon trucks, tanks or any other vehicle which may be used for war purposes.

An object of my invention is the provision of mounting the spring which permits the tilttable mounting to be tilted inside of a housing which will keep the twigs and bushes from becoming entangled in the spaces between the coils of the spring.

Another object of my invention is the provision of a tilttable mounting having a low electrical capacity so that there is very little loss of energy passing from the output of the radio signalling system over to the metal vehicle surface which carries the antenna.

Another object of my invention is the provision of a tilttable mounting for aerials which may be operated a large number of times without breaking or without requiring replacement.

Another object of my invention is the provision of a hollow metal tube for conducting the radio frequency from the radio frequency supply source to the aerial, in which the metal tube also functions as a housing for the spring which permits the tilttable operation of the mounting, so that twigs and branches of trees cannot become lodged between the spaces of the spring.

Another object of my invention is the provision of a tilttable mounting for aerials which is simple in construction and durable in operation.

Other objects and a fuller understanding of my invention may be had by referring to the following description and claims, taken in conjunction with the accompanying drawing, in which:

Figure 1 represents a side elevational view of a vehicle illustrating my tilttable mounting positioned on the top thereof for carrying an aerial;

Figure 2 is a cross-sectional view of my tilttable mounting for an aerial, taken along the line 2—2 of Figure 3;

Figure 3 is a plan view of my tilttable mounting for aerials;

Figure 4 is a side elevational view of my tilttable mounting for aerials; and

Figure 5 is a view similar to Figure 2 but shows the tilttable mounting being tilted to substantially a horizontal position.

My tilttable mounting is illustrated generally by the reference character 10 and comprises a base 13 and a tilttable sleeve 14 which carries the aerial 11. The base 13 may be mounted on a vehicle top 12 as illustrated in Figure 1. In fastening my tilttable mounting to a vehicle surface, a relatively large opening 36 is cut in the vehicle surface and the marginal edges of the base 13 are secured to the marginal edge of the opening 36 by means of suitable screws 29, as illustrated. The base 13 may comprise any suitable dielectric material and preferably the dielectric base should be as large as possible in order to make the capacity small which prevents the escape of radio frequency energy to the metal top 12 of the vehicle. The base 13 may be made into a plurality of sections comprising the sections 19, 20 and 21. In this manner, the leakage resistance may be kept large.

On top of the base section 19 is mounted a metal resting plate 17 and a contact plate 18 upon which the tilttable tube 14 is arranged to be tiltably mounted. The metal resting plate 17 and the contact plate 18 may be securely fastened to the top base section 19 by means of a hollow sleeve 22 which extends through all of the base sections 19, 20 and 21. The outside surface of the hollow sleeve 22 is provided with threads and the metal resting plate 17 is arranged to be threadably connected to one end of the hollow sleeve 22 and a nut 23 is arranged to be threadably connected to the other end of the hollow sleeve for holding the base sections 19, 20 and 21 together as well as the metal resting plate 17 and the contact plate on top of the base section 19.

The tilttable tube 14 has an enlarged bell portion 15 on the bottom end thereof which engages the metal resting plate 17. The bell portion 15 may be welded such as indicated by the reference character 16 to the lower end of the tilttable tube 14. The peripheral edge of the metal resting plate 17 is chamfered or rounded and the lower peripheral edge of the enlarged bell portion 15 is arranged to rest upon this chamfered or rounded peripheral edge of the metal resting plate in order to make a good metal to metal contact. In actual practice, the diameter of the metal resting plate 17 is slightly larger than the diameter of the peripheral lower edge of the enlarged bell portion 15 so that there is a slight tendency for the enlarged bell portion 15 to rock upon the chamfered or rounded peripheral edge of the contact metal resting plate 17. By means of this construction, a good metal to metal contact between the metal resting plate 17 and the peripheral lower edge of the enlarged bell portion 15 is always guaranteed.

Mounted within the tilttable tube 14 is a spring

32 having its lower end resting upon a stop member 33 that fits within the opening provided in the top central part of the enlarged bell portion 15. The upper end of the spring 32 presses against an anchoring member 31 which is securely fastened to the upper end of a cable 30 which extends downwardly through the spring 32 and which has its lower end 25 securely anchored to an anchoring screw 24. As illustrated in Figures 2 and 5 of the drawing, the anchoring screw 24 may be hollow for a portion of its length and in actual practice I provide for brazing or otherwise fastening the lower end of the cable 30 in the hollow portion of the anchoring screw 24. Similarly, the upper end of the cable 30 may be brazed or otherwise suitably fastened in the anchoring member 31. The wire 28 which leads from the radio signalling system may be fastened to the anchoring screw 24 by means of two nuts 26 and 27. The tension of the spring 32 may be varied by turning the nut 26 with reference to the anchoring screw 24, after which the wire 28 and the nut 27 may be tightened for holding the wire securely to the anchoring screw 24. The upper end of the tiltable tube 14 may be provided with a chuck 34 for releasably holding the aerial 11 upon the turning of the chuck sleeve 35.

In operation, when the vehicle passes under a limb of a tree or other bush, the antenna 11 may be tilted back until the vehicle passes under the obstruction. When the obstruction is cleared the antenna 11 is immediately raised to its vertical position. During the time that the tiltable tube 14 is being tilted, a good metal to metal contact is permanently made so that the radio communication is not interrupted. The enlarged bell portion 15 since it has a larger diameter than the diameter of the tiltable tube 14 provides for giving an initial stability to the aerial 11 before it is tilted back upon striking a branch of a tree or other obstruction. The base section 21 which is the section that is connected to the metal top of the vehicle, may be made large in diameter to reduce the capacity of the mounting to thereby prevent any loss of radio frequency energy escaping over to the metal top 12 of the vehicle. The tiltable tube 14 protects the spring 32 from direct contact with twigs or other obstructions that might lodge between the spaces of the coils of the spring and thereby keeps the mounting in complete operative condition under all adverse conditions. In addition, the tiltable tube 14 acts as a conductor for the high radio frequency energy and hence high frequency energy tends to flow to the outer surface of a conductor by reason of the electrical skin effect. In other words, in my invention there are no parts which are external of the tiltable tube 14 through which the high radio frequency would tend to pass by reason of the electrical skin effect. Therefore, the tiltable tube 14 not only performs a mechanical function to protect the spring from becoming clogged up with twigs and other objects, but also provides a good electrical conduction path for the high radio frequency to the aerial 11.

Although I have shown and described my invention with a certain degree of particularity, it is understood that changes may be made therein without departing from the spirit of the invention which are included within the scope of claims hereinafter set forth.

I claim as my invention:

1. In an aerial having a plurality of hollow members, the improvement of connecting joint means for the hollow members, said improvement

comprising first engaging means on one of the hollow members, second engaging means on another hollow member, said engaging means being adapted to engage each other and support the hollow members in a substantially fixed extended position with respect to each other, resilient means in one of the hollow members, bendable means connected to the resilient means in the said one of the hollow members and extending through the first and second engaging means to the said another hollow member, said bendable means and said resilient means exerting a constraining force upon said hollow members and constraining the first and second engaging means together to hold the hollow members in the said substantially fixed extended position, said bendable means upon movement of the hollow members from the said substantially fixed extended position being subjected to a bending movement and said resilient means being subjected to an axial movement free from said bending movement, terminal means having a contact portion engaging the said another hollow member, said bendable means being connected to the terminal means and constraining the said contact portion against said another hollow member, at least one of said engaging means having an outwardly sloping surface against which the other engaging means contact to limit longitudinal movement between the hollow members.

2. In an aerial having a plurality of hollow members, the improvement of connecting joint means for the hollow members, said improvement comprising first engaging means on one of the hollow members, second engaging means on another hollow member, said engaging means being adapted to engage each other and support the hollow members in a substantially fixed extended position with respect to each other, resilient means in one of the hollow members, bendable means connected to the resilient means in the said one of the hollow members and extending through the first and second engaging means to the said another hollow member, said bendable means and said resilient means exerting a constraining force upon said hollow members and constraining the first and second engaging means together to hold the hollow members in the said substantially fixed extended position, said bendable means upon movement of the hollow members from the said substantially fixed extended position being subjected to a bending movement and said resilient means being subjected to an axial movement free from said bending movement, said resilient means having its end which is next to the engaging means blocked in the said one of the hollow members and having its remote end connected to the bendable means, thereby being subject to compression, terminal means having a contact portion engaging the said another hollow member, said bendable means being connected to the terminal means and constraining the said contact portion against said another hollow member, at least one of said engaging means having an outwardly sloping surface against which the other engaging means contact to limit longitudinal movement between the hollow members.

3. A tiltable mounting for securing an aerial to a vehicle surface having an opening therein comprising, in combination, a base comprising dielectric material for covering the said opening, means for securing the marginal edge of said base to the marginal edge of the said opening, a metal resting plate mounted on the outside sur-

face of the base, a hollow sleeve extending through the base for holding the resting plate on the base, a flexible cable having a first end portion and a second end portion, said first end portion extending through the hollow sleeve, terminal means fastened to the first end portion of the cable which extends through the hollow sleeve, said terminal means engaging the hollow sleeve and anchoring the said first end portion of the cable to the hollow sleeve, a tilttable hollow metal tube having a first end with a socket arranged to tiltably rest on the metal resting plate and having a second end arranged to support the aerial, a spring positioned in the hollow tube, 10 said spring having one end engaging the tilttable hollow tube and having the other end engaging

5 the second end portion of the flexible cable for resiliently urging the first end of the tilttable hollow tube against the resting plate and thereby permitting the hollow metal tube to be tilted with reference to the resting plate under the action of the spring, said flexible cable means upon a tilting movement of the hollow tube being subjected to a bending movement and said spring means being subjected to an axial movement free from said bending movement, said metal resting plate having a diverging peripheral edge against which the socket engages, said socket resting on the diverging peripheral edge and limiting longitudinal movement between the hollow tube and the said plate.
